LINE LOCKING AND MARGIN RELEASING MECHANISM FOR TYPEWRITING MA- CHINES

Laurence B. Hill and Charles Walker, Syracuse,
N. Y., assignors to L. C. Smith & Corona Type-
writers, Inc., Syracuse, N. Y., a corporation of
New York

Application July 26, 1951, Serial No. 238,738

7 Claims. (Cl. 197—108)

1

The invention relates to improvements in line locking and margin releasing mechanism for typewriting machines.

The principal object of the invention, generally stated, is to provide improved means for automatically locking a typewriter against typing actuation at a desired marginal limit of letter feed travel of its platen carriage and for, at will, permitting typing in the reserved left and right hand marginal spaces on a paper sheet.

A further object of the invention is to provide simple and efficient margin stop controlled means for automatically locking the type actions and space bar action of a typewriter when the typing of a line has proceeded to a selected point, and improved margin release key means for unlocking said actions.

A further object of the invention is to provide improved key controlled means for disabling or releasing the margin stop means of a typewriter, to permit typing in reserved left and right hand margins, and for restoring an automatic line locking member of the typewriter to ineffective position.

To the foregoing and other ends which will appear, the invention consists in the features of construction, arrangements of parts and combinations of devices to be described hereinafter and particularly pointed out in the appended claims.

In the drawings, wherein the invention is illustrated in its preferred embodiment:

Fig. 1 is a fragmentary vertical, longitudinal sectional view of a typewriter equipped with line locking and margin releasing mechanism embodying the invention, the view being taken substantially medially of the typewriter on the line 1—1 of Fig. 7 and the parts being shown in normal rest position;

Fig. 2 is an enlarged detail view taken on the same line as Fig. 1, but showing the parts in line locking position;

Fig. 3 is a view similar to Fig. 2, but showing the margin release key means in margin releasing position with the lock still in locking position and ready for unlocking when the margin release key is released from finger pressure;

Fig. 4 is a fragmentary plan view of the typewriter with parts broken away;

Fig. 5 is a detail plan view of parts of the typewriter showing the adjustable right hand margin stop on the platen carriage in carriage arresting and line locking effecting position;

Fig. 6 is a view similar to Fig. 5 showing the position of the parts when the margin release key is depressed after a line locking operation; and

Fig. 7 is a fragmentary plan view illustrating certain parts of the machine in normal or rest position.

2

The platen 10 is mounted as usual on a carriage 11 which travels transversely of the main framework 12 from right to left under control of the usual escapement, not shown. Mounted in the main frame is a system of type bar actions only so much of which is shown as is necessary to an understanding of the invention. Said type bar action system includes four banks of type or printing key levers 13 fulcrumed on a pivot rod 14 supported on the frame. Each key lever has a pin and slot connection 15 with a different one of a set of bellcranks 16 which are of identical size and shape and are fulcrumed on a pivot rod 17 supported on the frame. Suitable operating linkages, shown in part at 18, connect the bellcranks with the type bars (not shown). Type bar action returning springs 19 are connected to the bellcranks and hold the actions yieldingly in rest position with the key levers 10 rocked upward against a key lever stop 20 which is fixed to a key lever guide comb 21 secured to the frame.

The known left hand margin stop 22 and right hand margin stop 23 are adjustable along and releasably latching to the margin stop bar 24 in a known manner, said bar extending longitudinally of the carriage 11 and being fixed thereto. The known left and right hand final or terminal stops 25 and 26 respectively, are fixed 30 to the stop bar.

A plate 27 is located behind the stop bar and medially of the sides of the machine and is fixed to a part of the main framework 12. A lever 28 is pivoted on plate 27 at 29, and a spring 30 is connected to the left hand arm of this lever to project the right hand arm of the lever forwardly and engage a stop lug 31 on said right hand arm with the forward end of a slot in the plate. A counter stop 32 for the left hand margin stop and a counter stop 33 for the right hand margin stop are disposed at different levels, one for engagement by an abutment portion 22a of stop 22 and the other for engagement by an abutment 23a of stop 23. Stop 23 has a cam surface 23b co-active with counter stop 33 to force said stop rearward and rock the lever 28 against the resistance of spring 30, as more fully hereinafter explained.

Lever 28 normally holds counter stops 32 and 33 in effective position and is rockable against the resistance of spring 30, by means hereinafter described, to retract them out of effective position. Stop 32 is slidably held to plate 27 to move in a fore and aft extending guide slot in said plate and has a stud 34 engaged in a hole in the right hand arm of lever 28 for shifting of stop 32 by the lever. Stop 33 is pivoted to the right hand arm of lever 28 at 35 and is connected to said lever arm by a spring 36 which normally holds the stop swung slightly toward the right away

from a stop lug 37 on the lever arm which is adapted to arrest leftward swinging of stop 33.

The counter stop controlling or shifting lever 28 is rockable against the resistance of its returning spring 30 by an upstanding rock arm 38 which extends up through a clearance slot 39 in plate 27 and has its upper end engaged in a hole in the right hand arm of said lever. Arm 38 is fixed to a horizontal rock shaft 40 which extends transversely of the machine under plate 27 from a point adjacent the right hand side of the machine and is journaled at 41-42. A rearwardly extending rock arm 43 is fixed to the rock shaft adjacent the right hand side of the machine, and the upper end of a link 44 is pivoted to the rear end of said arm at 45. The spring 30 connected to the left hand arm of lever 28 serves also as a return spring for the rock shaft and its rock arms and for the link 44.

The above described margin stop and counter stop devices and their mountings and the counter stop shifting means, are generally similar to those embodied in the known Smith-Corona standard typewriter and disclosed in the United States patent to Carl Gabrielson, No. 1,933,550, November 7, 1933. The improvements now will be described.

A horizontal stud 46 is fixed to the lower end of link 44 and extends through a closed up-and-down extending slot 47 in the rear end of a rearwardly extending arm of a bellcrank 48 which has a laterally offset pendant arm located adjacent the right hand side of the machine. Bellcrank 48 is journaled on a pivot rod 49 which extends horizontally and transversely of the machine and is fixed to framework 12. Stud 46 normally is located at the upper end of slot 47. At the right hand end of the set of type bar action bellcranks 16 there is fulcrumed on the bellcrank fulcrum rod 17 a line-locking bar controlling bellcrank 50 which has a forwardly extending forked arm and an upstanding arm. A fore and aft extending link 51 is pivoted at 52 to the lower end of the pendant arm of bellcrank 48 and is pivoted at 53 to the upper end of the upstanding arm of bellcrank 50. The bellcranks 48 and 50 and their connecting link 51 are normally yieldingly held in their rest position, shown in Fig. 1, by a returning spring 54 connected to the upstanding arm of the bellcrank 50. Return movement of the connected parts 48-51-50 is limited or arrested by the engagement of the lower branch of the forked arm of bellcrank 50 under a laterally extending stud 55 on a margin release key lever 56.

The margin release key lever 56 is fulcrumed on the key lever fulcrum rod 14, extends through one of the slots in the key lever guide comb 21, is normally held rocked up against the key lever stop 20 by a returning spring 57 connected to said key lever 56, and is located at the right hand side of the system of type key levers 13 with its key located at the right hand end of the rear or fourth bank of type keys.

A line locking bar 58 extends transversely of the machine above the forward and forked arm of bellcrank 50 and above the forward arms of the set of type bar action bellcranks 16. This bar is formed at each end thereof, at its forward edge with a bearing sleeve 59, which two sleeves are journaled on horizontal pivot studs 60 held to framework 12 at opposite sides of the machine and extending transversely of the machine to support the bar for up and down swinging. The rear edge of bar 58 is provided with a notch 58a

to afford working clearance for the upstanding arm of bellcrank 50. The upper branch of the forked forward arm of bellcrank 50 normally is engaged under the bar 58 to support the bar in a slightly upwardly and rearwardly inclined ineffective position thereof shown in Fig. 1. To afford an ample and rapid swinging movement of the bar in response to rocking of bellcrank 50 said upper branch of the forked arm thereof is formed at its forward end with an upstanding hump or cam portion 50a which normally is engaged with substantially the lowest part of a downwardly bowed cam lug 58b formed out of bar 58.

The bar 58 is movable downward by gravity, as more fully hereinafter explained, into a line locking position thereof, shown in Figs. 2 and 3, and is there arrested by engagement of the bar with an underlying and padded stop lug 61 on a stop bracket 62. Bracket 62 is supported by the right hand pivot stud 60 for the bar and by a fastening screw 63 held to the framework 12. To prevent accidental swinging of the bar upward and forward over center, the bracket is provided with an overthrow preventing stop lug 64 which overhangs the bar and is spaced slightly above the bar when the bar is in normal position.

The type bar action bellcranks 16 have their upstanding arms recessed to clear the line locking bar on the printing strokes of the type bar actions while the line locking bar is in normal position. Said bellcrank arms also have forwardly facing abutments 16a which normally are aligned across the machine and which engage the forward edge of the bar 58, after a slight depression of the type keys and a slight movement of the type bars, to prevent typing while the bar 58 is in its line locking position, shown in Fig. 2.

The carriage escapement (not shown) is actuated in known manner by a type bar actuated universal bar (not shown) with which the type bars make driving engagement, as is usual in the art, during a final short part of their printing strokes. Since the line lock bar, when in locking position, blocks printing strokes of the type bar actions when only a short initial part of such strokes is completed, the type actions not only are blocked against printing, but also are prevented from actuating the escapement. According to the present invention, the escapement actuating space bar action or mechanism of the machine includes novel means whereby the line lock bar also blocks actuation of the space bar mechanism when said line locking bar moves into locking position. This space bar mechanism now will be described.

An upstanding escapement actuating tappet lever 65 is journaled at 66 on frame 12 to rock fore and aft of the machine and is located substantially medially of the sides of the machine. The space bar 67 is supported by the usual rock arms 68 fixed on a rock shaft 69 journaled in frame 12. The shaft 69 has an upstanding rock arm 70 located medially of the sides of the machine and connected with the lower end of tappet lever 65 by a novel connection whereby the space bar mechanism may be line locked. A link 71 is pivoted at its rear end to the lower end of lever 65 at 72 and is pivoted at its front end at 73 at the juncture of the upstanding arm and the forwardly extending arm of an angular link 74. The forwardly extending arm of link 74 is pivoted at 75 to the upper end of rock arm 70, and the upstanding arm of link 74 is provided with an upwardly and rearwardly inclined supporting and

guiding slot 76 through which the bellcrank fulcrum rod 17 extends, said rod normally passing through the lower end portion of the slot.

A returning spring 77 is connected to lever 65 to return the space bar mechanism to the normal position shown in Fig. 1 in which a stop 78 on the space bar arm 68 is engaged under a stop 79 on frame 12. When the space bar is depressed to trip the escapement, an upstanding projection 80 on link 74 moves downward and rearward under the line lock bar while the latter is in its ineffective position, but when the line lock bar drops to its locking position its rear edge is located immediately in front of projection 80 and blocks depression of the space bar.

The improved line locking and margin releasing mechanism operates as follows:

As the carriage, in advancing toward the left under control of the escapement, approaches the end of the writing line for which the right hand margin stop 23 is set, the cam edge 23b of said stop makes engagement with the forward end of the counter stop 33 and first rocks the counter stop into arrested engagement with the stop lug 37 on lever 28 and then cams the counter stop and lever 28 into the position shown in Fig. 5, at which time abutment 23a of stop 23 engages the counter stop 33 and arrests leftward travel of the carriage at the selected right hand marginal point. Rocking of lever 28 into the position shown in Fig. 5, rocks the shaft 40 and thrusts the link 44 downward far enough to first take up the lost motion in the pin and slot connection 46-47 and to then rock the bellcrank 48 to thrust the link 51 forward and rock the bellcrank 50 into the position shown in Fig. 2, whereupon the line locking bar 58 gravitates into its line-locking position shown in Fig. 2 and blocks effective actuation of all of the type bar actions and of the space bar mechanism. In this line-locking position of the parts, the lower branch of the forward forked arm of bellcrank 50 is rocked downward slightly away from the stud 55 on the margin release key lever 56.

To release the line lock and permit typing in the right hand margin, as for completing a word or syllable, the key of the margin release key lever is depressed, rocking said key lever into the position shown in Fig. 3. This causes the stud 55 on said key lever to engage the lower branch of the forked arm of bellcrank 50 and rock said bellcrank farther into the position shown in Fig. 3, which action farther advances link 51 and bellcrank 48 to pull link 44 farther downward and cause the rock shaft 40 and rock arm 38 to rock the lever 28 from the position shown in Fig. 5 to the position shown in Fig. 6. This retracts the counter stop 33 from engagement with abutment 23a of the right hand margin stop 23, whereupon spring 36 swings counter stop 33 back into its normal spaced relation to stop lug 37 on lever 28 so that the front end of counter stop 33 is located to the right of abutment 23a and will not again block advance of the carriage when the margin release key is released. Depression of the margin release key also retracts the slidable counter stop 32 and is arrested by engagement of said counter stop with the rear end of its guide slot. When said key is released, the springs 30, 54 and 57 return the parts to their respective normal positions.

When the typing of a line is continued in the right hand margin, a final line locking is effected by a cam surface 26b on the right hand terminal stop 26 on the margin stop bar which acts on

counter stop 33 in the same manner as the cam surface 23b on margin stop 23. The abutment 26a of stop 26 engages counter stop 33 to finally arrest the carriage and extends so far rearward that counter stop 33 cannot be retracted by the margin release key far enough to clear said abutment. On return of the carriage after typing in the right hand margin, the abutment on the right hand margin stop 23 rocks the counterstop 33 rightward and by-passes the counter stop without arresting return of the carriage.

Arrest of return movement of the carriage at the left hand marginal position for which the left hand margin stop 22 is set occurs when the abutment portion 22a of margin stop 22 engages the left hand side of its slidable counter stop 32. Such arrangement has no effect on the line locking and margin releasing mechanism. To return the carriage farther, for typing in the left hand margin, the margin release key is depressed, as in the case of the release for the right hand margin, whereupon the parts of the line locking and releasing mechanism are forced by the margin release key lever to assume the position shown in Figs. 3 and 6 in which lever 28 has retracted the slidable counter stop 32 far enough to permit the abutment 22a to pass counter stop 32 when the carriage is shifted farther to the right.

On subsequent letter space advance of the carriage toward the left, the abutment 22a of margin stop 22 engages the beveled or cam surface 32a on the right hand side of the counter stop 32 and cams said counter stop rearward until abutment 22a passes the counter stop. This rearward movement of the counter stop 32 rocks the lever 28 only part way from its normal position toward its line locking effecting position of Fig. 5, and rocks the shaft 40 only far enough to drive link 44 downward sufficiently to take up, or substantially take up, the lost motion in the pin and slot connection 46-47, so that no movement of the line locking bar 58 occurs.

Return of the carriage beyond the point for which the left hand margin stop 22 is set is limited by engagement of the left hand final or terminal stop 25 on the margin stop bar with an abutment or shoulder 81 on plate 27.

We claim:

1. A typewriting machine having, in combination, a platen carriage reciprocable in letter feeding and return directions, a set of key-operated type bar actuating levers, a margin release key lever having a lateral projection, a return spring connected to said margin release key lever, a return stop for said margin release key lever, a line locking member mounted for gravitational movement from an ineffective position into a line locking position in which it blocks effective actuation of said type bar actuating levers, a stop engageable by said member to arrest it in line locking position, a controlling lever for said line locking member, a return spring connected to said controlling lever to normally hold it rocked against said member and the projection on the margin release key lever to yieldingly hold said member in its ineffective position, a margin stop mounted to travel with the carriage, and means controlled by said margin stop for rocking said controlling lever out of engagement with said member and projection to permit said member to move to line locking position and then arresting letter feeding travel of the carriage, said margin stop controlled means being operable to free the carriage for further letter feed travel by a further rocking of said control-

ling lever by said margin release key lever projection when the margin release key lever is moved against the resistance of its return spring.

2. A typewriter machine having a frame, a carriage movable across the frame in letter feed and return directions, a line locking member mounted on the frame for gravitational movement from an ineffective position into an effective position, a stop for arresting said member in effective position, a right hand margin stop mounted to travel with the carriage, a margin release key lever fulcrumed on the frame, a return spring and a return stop for said key lever, a control lever fulcrumed on the frame, a return spring for said control lever normally holding said lever rocked into engagement with said key lever and said line locking member to support said member in ineffective position, and counter stop mechanism for said margin stop mounted on the main frame and connected with the control lever for retraction out of effective relation to said margin stop when said key lever is rocked away from its stop and for partial retraction of said mechanism by said margin stop to rock said control lever out of engagement with said key lever and line locking member preliminary to arrest of letter feed movement of the carriage by said margin stop and counter stop mechanism.

3. A typewriting machine having a carriage movable in letter feed and return directions, left and right hand margin stops mounted to travel with the carriage, counter stop mechanism for said margin stops mounted for movement from an effective position to an ineffective position and movable by the right hand margin stop to an intermediate position preparatory to arrest of letter feed movement of the carriage, a margin release key lever, a return spring and a return stop for said key lever, a control lever connected with said counter stop mechanism, a spring for rocking said control lever to a normal position in which it is arrested by and abutted with the key lever for rocking of the control lever by the key lever to a position in moving into which the control lever moves the counter stop mechanism to its ineffective position, said control lever being movable relatively to the key lever to an intermediate position by said counter stop mechanism as the latter is moved to its intermediate position by the right hand margin stop, and a line locking member mounted for gravitational movement to an effective position from an ineffective position to which it is movable by the control lever and in which it is normally seated against the control lever.

4. A typewriting machine, as claimed in claim 3, wherein said left hand margin stop during letter feed travel of the carriage, and said right hand margin stop during return travel of the carriage, respectively are adapted to shift the counter stop mechanism part way to its intermediate position to by-pass said mechanism after typing respectively in the left and right hand margins, wherein there is provided a lost-motion operating connection between said mechanism and the control lever to permit such shifting of the counter stop mechanism by said margin stops without rocking of the control lever from its normal position, and wherein separate springs are connected to the counter stop mechanism and the control lever respectively, for moving them to their respective normal positions.

5. A typewriting machine having a carriage reciprocal in letter feed and return directions, a set of key-operated type bar actuating levers, a

horizontal fulcrum rod for said levers, a line locking member mounted for gravitational movement from an ineffective position into a line locking position in which it is engageable by said type bar actuating levers to block effectual actuation of the latter, a control lever fulcrumed on said rod and on which said member normally is seated, a return spring connected to said control lever, a margin release key lever in abutment engagement with which the control lever normally is held by its return spring and which is actuated to rock the control lever to a margin releasing position, a return spring and return stop for the margin release key lever, a space bar mechanism including a link guided on said fulcrum rod to normally move transversely of the rod upon actuation of said mechanism and to be blocked against such movements by the line locking member when the latter is in line locking position to thereby block effectual actuation of the space bar mechanism, a pair of margin stops mounted to travel with the carriage, and counter stop mechanism for said margin stops connected with said control lever for movement to an ineffective position by movement of said control lever to its margin releasing position, one of said margin stops being operable on said counter stop mechanism to move said mechanism part way to its ineffective position to thereby rock said control member far enough to permit the line locking member to gravitate into its line locking position.

6. A typewriting machine having a carriage movable in letter feed and return directions, a set of key-operated type bar actuating levers, a horizontal fulcrum rod for said levers, a line locking bar pivoted to swing about an axis which is parallel to said rod and adjacent one longitudinal edge of the bar, a stop underlying said bar to arrest gravitational movement of the bar at a line locking position in which the bar blocks effectual actuation of said type bar actuating levers, a margin release key lever fulcrumed to rock about an axis which is parallel to said fulcrum rod, a return spring and a return stop for said margin release key lever, a control lever fulcrumed on said fulcrum rod and normally abutted with said key lever and said line locking bar to hold the bar elevated above said stop in an ineffective position in which the type bar actuating levers are effectually operable, a spring urging said control lever against said bar and key lever, and line end stop mechanism for rocking the control lever at a selected letter feed position of the carriage to permit the line locking bar to gravitate into engagement with its underlying stop and releasable by said control lever to permit continued letter feed travel of the carriage beyond said letter feed position.

7. A typewriting machine, as claimed in claim 6, having a second stop which overhangs the line locking bar in its ineffective position.

LAURENCE B. HILL
CHARLES WALKER.
